UNITED STATES PATENT OFFICE.

SAMUEL KRAMER AND ABRAHAM KRAMER, OF BROOKLYN, NEW YORK.

DESIGN FOR A WALL BRACKET.

Application filed June 24, 1924. Serial No. 9,959. Term of patent 3½ years.

To all whom it may concern:

Be it known that we, SAMUEL KRAMER and ABRAHAM KRAMER, both citizens of the United States, and residents of Brooklyn, in the county of Kings and State of New York, have invented a new, original, and ornamental Design for Wall Brackets, of which the following is a specification, reference being had to the accompanying drawing, forming a part thereof, in which—

Fig. 1 is a front view, and
Fig. 2 is a side view.

We claim:

The ornamental design for a wall bracket,
as shown.

SAMUEL KRAMER.
ABRAHAM KRAMER.
